UNITED STATES PATENT OFFICE.

JOHN F. O'CONNOR, OF CHICAGO, ILLINOIS, ASSIGNOR TO WILLIAM H. MINER, OF CHAZY,
NEW YORK.

FRICITION DRAFT-RIGGING

1,303,874.

Specification of Letters Patent. Patented May 13, 1919.

Application filed March 28, 1917. Serial No. 156,914.

To all whom it may concern:

Be it known that I, JOHN F. O'CONNOR, a citizen of the United States, residing at Chicago, in the county of Cook and State of Illinois, have invented a certain new and useful Improvement in Friction Draft-Rigging, of which the following is a full, clear, concise, and exact description, reference being had to the accompanying drawings, forming a part of this specification.

This invention relates to improvements in friction draft rigging.

As is well known there are many thousands of freight cars in service which are equipped with tandem spring gears which include the usual tandem side castings having main front, rear and middle stops and corresponding limiting stops. Due to the constantly heavier service demanded of freight cars, the railroads have been compelled to increase the strength of the underframes of old cars and, in many instances, to provide heavier draft gears than those of the spring type.

The object of my invention is to provide a novel form of friction gear of heavier capacity than tandem spring gears and which may be employed in combination with the usual tandem stop castings now found on old cars whereby to effect a large saving to the railroads since they can employ the old stop castings or cheek plates with the improved heavier friction gear.

In the drawing forming a part of this specification, Figure 1 is a longitudinal vertical section of a draft rigging showing my improvements in connection therewith. Fig. 2 is a horizontal sectional view taken substantially on the line 2--2 of Fig. 1. Fig. 3 is a view similar to Fig. 1, but illustrating the position of the parts under full buff. Fig. 4 is a transverse vertical section taken on the line 4--4 of Fig. 1. And Fig. 5 is a detailed perspective view of one of the intermediate followers.

In said drawing, 10--10 denote draft sills to the inner faces of which are secured tandem stop castings A--A of a well known form. Each of said stop castings A is provided with the usual main front stop shoulder 11, main rear stop shoulder 12, main intermediate stop shoulders 13 and 14, and corresponding limiting stops 15, 16, 17 and 18.

The improved friction gear, which is

adapted to be used in connection with the usual type of tandem stop castings, comprises front and rear followers 19 and 20, intermediate followers 21 and 22, front spring 23, rear spring 24, vertically movable wedge blocks 25--25, vertically movable triangular shaped wedges 26--26, longitudinally movable wedges 27, 28 and 29, plungers 30 and 31, and supplemental spring followers 32 and 33. Each of the end followers 19 and 20 is of the usual form but each intermediate follower is provided on its inner face with opposed oppositely inclined wedge surfaces 34--34 which cooperate with the inclined ends of the wedge blocks 25, as clearly shown in Fig. 1. Furthermore, each of the intermediate followers is provided with spaced upper and lower arms 35--35 that extend between each intermediate follower and its corresponding adjacent end follower so that each set of end and intermediate followers is maintained at a fixed distance apart. On the side nearest the spring, each intermediate follower is recessed, as indicated at 36, to form a seat for the corresponding supplemental spring follower 32 or 33, the latter having the plungers 31 and 30, respectively, formed integrally therewith and extending through suitable central perforations 37 in the intermediate followers. The plungers 30 and 31 preferably have formed integrally therewith the wedges 27 and 29, respectively. As will be understood, all of the wedge elements are of such a width as to be readily accommodated between the center posts of the stop castings A--A, as shown in Fig. 2. As also shown in said figure, the intermediate followers 21 and 22 are normally in engagement with their corresponding limiting stops 17 and 18 and not with the main stops 13 and 14, respectively. The reason for this will appear from the description of the operation hereinafter. All the parts of the gear are connected to the draw bar 40 by means of a yoke 41 and saddle plates 42--42 may be employed to support the parts in position.

The operation is as follows: Upon inward movement of the draw bar, it is obvious that the front follower 19 and front intermediate follower 21 will move inwardly in unison, whereas the rear follower 20 and rear intermediate follower 22 will remain stationary. As the front set of followers moves inwardly, the wedge blocks 25--25 will be

forced toward each other, that is, vertically toward the center line of the gear due to the relative approach of the opposed sets of wedge surfaces 34 on the intermediate followers. This causes the triangular wedges 26-26 to approach each other and they in turn compel the separation of the three wedges 27, 28 and 29 to the position indicated in Fig. 3. As the wedges 27, 28 and 29 are separated, it is apparent that the plungers 30 and 31 will be actuated and consequently the supplemental followers 32 and 33, thus compressing both sets of springs simultaneously. In draft, the front set of followers 19 and 21 will remain stationary and the rear set 20 and 22 will move forwardly in unison, causing similar action of the friction elements and simultaneous compression of the springs.

20 The construction herein shown and described may be manufactured at relatively small expense and affords an economical arrangement for railroads, since it permits them to reemploy the old tandem stop castings while at the same time obtaining a gear of much heavier capacity and better suited for the present conditions of service.

I claim:

1. In a draft rigging, the combination with tandem stop castings having the usual end and intermediate main stops and corresponding limiting stops, of tandem arranged end and intermediate followers, the intermediate followers normally engaging their respective intermediate limiting stops, tandem arranged springs, friction elements located between the intermediate followers and between the center posts of said stop castings, and means for moving either end follower and the nearest intermediate follower simultaneously in the same direction to thereby compress the springs and actuate the friction elements.

2. In a draft rigging, the combination

with tandem stop castings having the usual end and intermediate main and limiting stops, of front main and intermediate followers moveable in unison in the same direction, rear main and intermediate followers moveable in unison in the same direction, tandem arranged springs, and friction elements between the intermediate followers and between the intermediate main stops of the tandem castings, said friction elements being actuated upon movement of either set of end and intermediate followers.

3. In a draft rigging, the combination with tandem stop castings, of end followers, intermediate followers, the latter being provided on their opposed inner faces with integral, oppositely arranged wedging surfaces, springs interposed between the end and intermediate followers, a plurality of friction elements coöperable with said wedge surfaces, means for holding the rear intermediate follower stationary when the rear end follower remains stationary, means for holding the front intermediate follower stationary when the front end follower remains stationary, and means for compressing the springs in a direction from the intermediate followers toward the end followers during either buff or draft.

4. In a draft rigging, the combination with tandem stop castings having the usual end and intermediate main stops and corresponding limiting stops, of end followers normally engaging the end stops, intermediate followers normally engaging their corresponding limiting stops, springs between the end and intermediate followers, and a plurality of friction elements interposed between and actuated by the intermediate followers.

In witness that I claim the foregoing I have hereunto subscribed my name this 7th day of March, 1917,

JOHN F. O'CONNOR.
